UNITED STATES PATENT OFFICE.

FRANK REES, OF NEW YORK, N. Y.

REPEATING FIRE-ARM.

SPECIFICATION forming part of Letters Patent No. 337,992, dated March 16, 1886.

Application filed April 17, 1885. Serial No. 162,546. (No model.)

To all whom it may concern:

Be it known that I, FRANK REES, of the city, county, and State of New York, have invented an Improvement in Repeating Fire-5 Arms, of which the following is a specification.

In this repeating fire-arm a magazine is made use of, the same being placed beneath the barrel, and a revolving carrier is employed for receiving the cartridge from the magazine 10 and elevating the same to the level of the barrel, a sliding breech-pin forces the cartridge out of the carrier into the barrel, and supports the same during the explosion, and withdraws the cartridge-shell. The revolving carrier simultaneously conveys down the spent shell 15 and elevates another cartridge into line with the barrel.

One especial feature of the present invention consists of a spring-barrel and endless chain 20 and chain-wheels to gearing by which the carrier is revolved and the proper motions given to the other parts of the gun. This mainspring barrel is wound with a key once for every sixteen shots or more, depending on the 25 length of the spring, and the construction of the parts is such that when the trigger is pulled the arm is fired. Upon the second pull of the trigger the aforesaid spring-barrel revolves the parts so that the spent cartridge is withdrawn from the barrel and lowered from the 30 line of the barrel to the line of the magazine, a fresh cartridge is elevated by the carrier and forced into the barrel by the steadyng breech-pin and held there firmly, and the parts are 35 then in position for firing; hence the only movement necessary in operating this repeating-arm by the person using it is to pull the trigger to fire, and to pull the trigger a second time to reload, the power for all other purposes being derived from the mainspring-barrel.

In the drawings, Figure 1 is an elevation of the mechanism of the gun with the side plates removed. Fig. 2 represents the butt-frame 45 with the wooden cheeks removed, showing the spring-barrel and chain-belt. Fig. 3 is a section of the butt and plan view of the spring-barrel. Fig. 4 is a detached plan view of the trigger and its sear. Fig. 5 is an elevation of 50 the lock-frame and the spring-door covering the chamber, through which the loaded cartridges are inserted into the magazine and the

empty cartridges ejected, and the mechanism connected with the same. Fig. 6 is an end view of Fig. 5. Fig. 7 is a detached view of the spring-door and section of its hinge. Fig. 8 is a section at the line *x* *x* of Fig. 5. Figs. 9, 10, and 11 are detached views representing the stop-gate at the front end of the filling and ejecting chamber and the shaft for actuating the same. Fig. 12 is a plan of the breech-pin and section of the lock-frame. Fig. 13 is a section of the breech-pin. Fig. 14 is an end view of the piston upon the firing pin. Fig. 15 is a front end view of the breech-pin. Fig. 16 is a section of the lock-frame and the revolving carrier. Fig. 17 is a rear view of the revolving carrier. Fig. 18 is a plan view of the lock-frame and parts of the revolving carrier. Fig. 19 is a section immediately at the 70 rear end of the barrel and magazine. Fig. 20 is a longitudinal section at the line *y* *y* of Fig. 19. Fig. 21 shows the inner face of the revolving tumbler and the shaft of the same. Fig. 22 is an end view of the carrier-shaft, 75 showing the pinion on its end. Fig. 23 is an end view of the cam-disk stud and toggle-link acted upon by said stud. Fig. 24 is a separate view of the sear and sear-arm for the firing pin. Fig. 25 is a separate view of the 80 trigger sear-stop. Figs. 26 and 27 show a modified form of the parts for ejecting the cartridge.

The barrel A is either rifled or plain, and the magazine-tube C extends along beneath the same, and is either a half or full length magazine, and it is retained in its place by the ordinary middle band and the wooden forearm B.

Within the magazine-tube C is the spring *c* 90 and the piston *c'*. This piston is provided with a projecting rib or ring, 1, and there is a sliding catch, *c*², beneath the forearm and a finger-piece, *c*³, by which the catch *c*² can be moved. These parts are shown in Figs. 19 95 and 20. When the cartridges have all been withdrawn from the magazine, the end of the piston *c'* projects into the revolving carrier and prevents the carrier from being revolved by the mechanism hereinafter described, but 100 when the finger-piece *c*³ and catch *c*² are moved by hand forward and lengthwise of the magazine-tube, the piston *c'* is carried into the said magazine-tube, and the carrier can then be

revolved. It is to be understood that this piston c' is pressed forward along the magazine-tube by the cartridges as they are passed in by hand, as hereinafter detailed. The rear 5 end of the barrel is received by and supported at the front end of the housing E, which extends to the rear as a butt-frame, D, terminating with the stock-plate D², and there are wooden cheek-pieces D³, of ordinary character, extending up to the housing E, and there are removable side plates, E' and E², and these are secured in place by screws introduced into the holes 22. These side plates are recessed or made cylindrical, as shown in Fig. 10 19, to give room for the carrier to revolve.

F is the trigger-guard, which may be of any desired shape, but it is preferably in the form represented, so as to guard both the trigger F' and the safety finger-piece hereinafter 15 spoken of.

The revolving carrier G is made as represented in Figs. 1, 16, 17, and 18, and has two cartridge-chambers, and at one side of each chamber there is a longitudinal slot, so that 20 25 the revolving carrier is S-shaped. This carrier is also grooved longitudinally (see Fig. 17) within the chambers, for the passage of the cartridge-extractor and finger that are connected with the breech-pin, as hereinafter 30 described. The shaft or axle g of the carrier extends through the same into the housing, and the carrier is firmly united thereto by set-screws 5, passing into the carrier laterally, and this shaft g extends through a hole in the 35 lock-frame I², which supports it, and there is a pinion, g', on the rear end of this shaft, g, by which the carrier is made to revolve intermittently. The fixed lock-frame I² is within the housing E, and is removable therefrom, 40 together with all the parts carried by such lock-frame, and when in place it is retained by screws r^3 or other suitable fastenings.

At the rear end of the stock, and within the butt-frame D, is a spring-barrel, H, containing 45 a compensating coiled spring of suitable size and strength. The axis of this spring-barrel passes through forked bearings h, that project forward from the lever h', which is pivoted at 4 to the stock-plate D², and at the other end 50 there is a tightening-screw, h², with a bridle-nut that acts upon the lever h', to tighten the chain H² by drawing back the spring-barrel. The axis of the spring-barrel is made 55 with a ratchet-wheel, h', that is held by a pawl upon the forked bearing h, and said axis terminates at one side as a square, h³, for a winding key or crank of any suitable character, that is applied to wind up the coiled spring at any time previous to the firing of 60 the gun.

The endless chain H² is of any suitable character. I prefer the semicircular flat riveted links shown, and the corresponding wheel upon the spring-barrel that receives the chain 65 has circular notches upon its periphery to interlock with the links of the chain.

In order to lead this chain from the spring-

barrel to the loading and firing mechanism in the most convenient manner, and without varying the ordinary shape of the gun-stock, I use the guide-pulley H¹, beneath which such chain passes, and this chain is endless and passes around the chain-wheel I, Fig. 5, which is at the side of a cam-disk, i², hereinafter referred to. The axis i of the chain-wheel I passes through the rear end of the fixed lock-frame I², and at the opposite end of such axis i is the tumbler K. This tumbler K is held by the trigger-sear and allowed to revolve progressively, as hereinafter shown, and upon the 80 inner face of the tumbler K are gear-teeth 7. (See Fig. 21 and dotted lines in Fig. 1.) There are half as many teeth upon this tumbler as there are upon the pinion g', which is at the rear end of the carrier-shaft g, and upon the 85 inner face of the tumbler there are also flat projecting surfaces or ribs 6, and upon the shaft g, behind and adjoining the pinion g', there is a square block, i³, (see Figs. 18 and 22,) the purpose of the ribs and square block 90 being to stop the revolution of the carrier and hold it in its proper place by one of the flat ribs 6 coming in flat contact with the flat sides of the square block i³ after the last tooth of 7 has separated from the teeth of the pinion g'. 95 It will now be understood that the carrier G receives a half-revolution for each complete revolution of the wheel I, shaft i, and tumbler K, and that the flat ribs 6, at the side of the carrier-stop i³, hold the carrier-pinion and carrier both before and after the teeth 7 give to the carrier the said half-revolution, thus preventing any incorrect or loose motion of the revolving carrier before the breech-pin enters the same, or after such breech-pin has 100 been withdrawn. When the breech-pin is within the carrier, it cannot be revolved, as the breech-pin holds it firmly in proper position. The breech-pin L is cylindrical at its front end, and the rear part is square and it slides within the stationary lock-frame I². At the rear end of the breech-pin the toggle-links L³ and L⁴ are connected, the latter being hinged at r^2 to the housing. These parts are located in such a manner that the central 110 joint, r^3 , of the toggle-links can pass slightly above the straight line between the other two joints, so that when the explosion takes place the joint r^3 will be forced toward the housing E and be supported thereby, and there is a 115 spring, l², between the joint r^3 and the housing E, which spring throws the joint r^3 downward, bending the toggle L³ L⁴ as soon as the cam, which holds up the toggle from below, is 120 released forward and releases such toggle. 125

Upon the inner face of the cam-disk i² is a cam-block, i⁴, (see Figs. 16 and 18,) and at one side of the toggle-link L⁴ is a projecting stud, 25. (See Fig. 23.) This cam-pin i⁴ acts beneath the projecting stud 25, to raise the toggle past the center and hold up the same during the firing of the gun; but as soon as the shaft i commences to revolve the cam-pin i⁴ is moved from and away from beneath the projec- 130

tion 25, and the toggle is liberated and bent downward, as aforesaid, by the spring t . The breech-pin L is moved backward and forward by the connecting-rod l , extending from the pin t upon the tumbler K to the pin l' , that projects from the side of the breech-pin near its front end. The pin l' being at the opposite part of the tumbler K to the teeth 7, these teeth 7 act to revolve the carrier G when the link l and crank-pin t have acted to draw the breech-pin L back out of the revolving carrier G, and it is to be understood that the pin l' is upon a block projecting from the side of the breech-pin L, and that this block slides lengthwise of the slot in the side of the carrier, and when this breech-pin is withdrawn the block at its side passes into a notch in the side of the stationary lock-frame L^2 . (See Fig. 12.)

On the upper front part of the breech-pin is a cartridge-extractor, o' , formed of a stiff spring with a hooked end, and opposite to the same, on the under side of the breech-pin, I prefer to make use of a finger, o^2 , which becomes a support for the rear end of the cartridge, so that the same is withdrawn with facility, and this extractor o' and finger o^2 slide within the grooves in the revolving carrier G, before named, and when the breech-pin is withdrawn the revolving carrier shoves the empty cartridge-shell out sidewise from between the finger o^2 and extractor-spring o' . The revolving carrier is cut away at 20 and 21, so that the projecting ends of the finger and extractor do not interfere with the revolution of the carrier G.

The breech-pin is hollow and contains the firing-pin n , around which is a helical expansive spring, n' , acting against the piston n^4 . This piston slides within the tubular portion of the breech-pin L, and its periphery is notched, as shown in Fig. 14, to allow the air to pass freely from one side of the piston to the other. A cylinder is made with the firing-pin to give it more weight. The front end of the firing-pin passes through a hole in the recoil-block at the front end of the breech-pin L. The firing-pin extends to the rear through the breech-pin and terminates with a catch-block, n' , sliding in a slot in the square portion of the breech-pin, and above this is a sear, n^2 , with journals 8, working in the stationary lock-frame I^2 , and from one of these journals an arm, n^3 , extends down. This is shown in the detached view, Fig. 24, and is hereinafter described. When the breech-pin is drawn back, the firing-pin is moved with it, and the catch-block n' passes beneath the spring-sear n^2 , and when the breech-pin comes forward again the hook-end of this sear holds the block n' and detains the firing-pin n , so that the firing-pin spring n' is compressed ready for firing, and when the parts are in position for firing it is only necessary to press against the sear-arm n^3 and unlatch the sear, liberating the firing-pin, and the spring n' projects said firing-pin against the fulminating-cap in the rear end of the cartridge.

It is to be understood that when the breech-pin is drawn back it carries with it the firing-pin n , and the extreme front end of such firing-pin would project from the end of the breech-pin; hence there would be a risk of exploding the cartridge when the breech-pin was driven forward to force the loaded cartridge out of the carrier G into the barrel. To prevent this contingency, I withdraw the firing-pin entirely into the breech-pin by means of the set-back o . This is in the form of a spring cam-lever (see Figs. 12 and 13) pivoted at 22 in a longitudinal mortise in the side of the square portion of the sliding breech-pin L, and the rear portion of this set-back is made as an incline, (see Fig. 12,) and as the breech-pin L is drawn back the set-back runs into contact with the projection o' , and by it the set-back o is forced inwardly, and the inclined rear end of such set-back acting against the front end of the catch-block n' forces the same back and draws the firing-pin with it, so that the end is within the front end of the breech-pin. As the breech-pin is forced forward, and carries the loaded cartridge with it, the sear n^2 catches the block n' , holding back the firing-pin, and in this movement of the breech-pin the set-back o is carried with it, so that it passes away from the stationary projection o , and the spring of the set-back throws the same into the position shown in Fig. 12, where it is out of the way of the block n' when the firing takes place.

The trigger F is provided with a trigger-spring, f' , (see Figs. 1 and 4,) and s is a trigger-sear hinged to the trigger, the pin 26 forming the pivot for both the sear and the trigger, and s^4 is a sear-spring attached upon the flat upper portion of the trigger, as seen in Fig. 4, and acting beneath a pin projecting laterally from the sear s , and acting to move the sear s backwardly or toward the trigger-latch f^3 .

The joint between the sear s and trigger F is a stop or rule joint, so that when the trigger is pulled the sear s is pressed forward.

Upon reference to Fig. 1 it will be seen that the tumbler K is stopped or locked by the upper end of the sear s , and that the spring-barrel and chain cannot now revolve said tumbler, and the arm n^3 of the sear n^2 is close against the front of the sear s ; hence when the trigger is first pulled the sear s , acting upon the arm n^3 , unlatches the sear n^2 , and the gun is fired.

I provide upon the tumbler K a notch at 26', and this holds the end of the sear s so that it cannot move back after the firing; but the trigger moves by the action of the spring f' opening the rule-joint between the trigger and the sear, and allowing the trigger-latch s' , that is pivoted upon the trigger, and provided with a spring, s^4 , to fall into a notch upon the sear s , so that when the trigger F' is pulled a second time the sear s is carried farther forward (by the action of the trigger-latch s') and the upper end of the sear s is moved entirely clear of the tumbler K, so that said tumbler K makes

nearly a half-revolution, and the part 26' of the tumbler K is arrested by the trigger-hook f^3 . During this half-revolution the pin t^2 and link l draw back the breech-pin L and extract 5 the cartridge-shell, drawing the same into the upper chamber of the carrier G, the toggle-links L^3 L^4 folding downwardly. As soon as the pressure on the trigger F' is relieved, the hook f^3 liberates the tumbler K, and said tumbler K is turned by the spring-barrel and chain and gives to the carrier G a half-rotation, as before described, bringing a loaded cartridge 10 up into line with the barrel and carrying down the empty cartridge-shell into line with the magazine. This takes place while the crank-pin t^2 is turning its rear dead-center, and there is very little motion given to the breech-pin; but as soon as the teeth 7 separate from the pinion g^1 the breech-pin is projected forward 15 through the carrier G, forcing the cartridge into the barrel and cocking the firing-pin, as aforesaid. During the first half-revolution of the tumbler K its end near the notch 20 26' acts upon the tail of the trigger-latch s' , unlatching the same and allowing the sear s to be moved by its spring s^4 into the normal position, so that when the tumbler K completes its rotation it is arrested by the 25 upper end of the sear s in the position shown 30 in Fig. 1, ready for the arm to be again fired. The spring n^5 returns the arm n^3 of the sear to its normal position, and this arm n^3 might be made in one piece; but I prefer to make it in two pieces jointed together, as shown, in order 35 that a device may be added so that the firing-pin may be detained when the other parts of the gun are moved for withdrawing a loaded cartridge without firing it. With this object in view I make use of a small vertical shaft, 40 t^1 , at the lower end of which is a finger-piece, t^2 , by which such shaft t^2 can be partially rotated and the safety-lock t brought into the path of the projecting end n^6 of the sear arm, n^3 , so that when thus turned the lock t , coming 45 against the end of the projection n^6 prevents the trigger being moved and locks it safely, and I make use of a friction-spring, u , with a conical end entering recesses in the safety-lock t , so as to hold the same in any position into which it may be turned. In the 50 normal position the lock t should be turned against the projecting end n^6 , so that the arm cannot be accidentally discharged, and when the gun is raised to the shoulder the lock t is thrown aside by the pressure of the trigger-finger against the projecting piece t^2 . Upon the upper part of this same shaft t is an arm, t^4 , and upon the sear-arm n^3 is a projection, 55 28, near the joint 29. When the finger-piece t^2 is turned sufficiently to bring the arm t^4 behind the projection 28, the sear-arm n^3 and sear cannot be moved; hence the firing-pin can be held, but the jointed lower end of the sear-arm may be swung upon the pivot 29 by 60 the upper end of the sear s , and hence the said sear s can be moved out of the way of the revolving tumbler K, so as to allow the said tum-

bler K to revolve and draw back the loaded cartridge and convey the same down to the ejecting-chamber, where it is taken out or else 70 passed forward into the magazine.

In the fixed lock-frame I² there is a chamber in line with the magazine, the same forming a filling and ejecting chamber, M, the inner surface of which is semicircular, and the back end is a semicircular incline, and there is a door, m , to this filling and ejecting chamber. A pin, 12, passes in at the front end and connects the hinge of the door to the lock-frame, and around this pin 12 is a helical spring, 11, one end of which is fastened to the pin 12, and the other end to the hinge of the door m , and there is a clamping-screw, 10, the head of which serves to bind upon the flange end of the pin 12, so as to hold the 80 said pin and the spring at any point to which it may be moved, and thereby regulate the power of the spring 11 to close the door m . There is a shaft, p , running along through the lower portion of the lock-frame I² and 85 forming a pivot for the rear hinge of the door m , and beyond that hinge the shaft p is square and enters a corresponding square hole in the ejector P. This ejector P is in the form of a curved finger occupying a recess in the lock-frame I² at one side of the filling and ejecting chamber M. At the back end of this shaft p there is an arm, p' , and a link, r^2 , attached to the cam-arm r . This arm r is upon a shaft, r^1 , in the bottom of the lock-frame I², and when the cam-disk r^3 is revolved, as heretofore described, its projection presses upon the arm r , and by the link r^2 moves the arm p' , shaft p , and ejector P, causing it to open the door and throw out the cartridge. A shoulder on the 90 ejector opens a door as the ejector throws out the cartridge. The spring r^3 returns the ejector to its normal position.

At the front end of the stationary lock-frame there is a gate, q , at the end of a shaft, q' , which is in line with the axis r' , and there is a finger, 14, on the rear end of the axis r' , and a finger, 15, on the front end of the shaft q' , and these fingers come side by side, but at a little distance from each other. The edge of 115 the gate q next the filling and ejecting chamber M is curved to correspond to the shape of said chamber, and there is a friction-spring, q^2 , bearing against the gate q , so as to hold the same in any position to which it may be 120 swung, and there is a thumb-piece, q^3 , at one side of this chamber M and extending out beyond the stationary lock-frame I², and there is a pin, q^4 , projecting from the thumb-piece q^3 and adjacent to the gate q . When the door 125 m is thrown open, by pressing upon the thumb-piece q^3 , so as to open the chamber M, the cartridges can be placed in through that chamber M and through the lower chamber in the carrier G into the magazine-tube C, and when the desired number of cartridges have been inserted the thumb-piece q^3 is pressed inwardly, and the gate q is swung sufficiently to partially 130 close the end of the chamber M and

prevent the cartridge passing back into said chamber, and when the door *m* is closed the edge of it presses back the thumb-piece *q*³ out of the way to its normal position, but leaves the gate *q* unmoved. After the arm is fixed the first revolution of the wheel *I* causes the cam-disk *i*² to press down the arm *r*, partly turn the shaft *r'*, and by the finger 14 moves the finger 15, shaft *q'*, and gate *q* so as to swing the same out of the way of the cartridge-shell, which is brought down and into the ejecting-chamber to be ejected by the next revolution of the wheel *I*.

It is to be understood that the empty cartridge-shell is shoved back into the ejecting-chamber *M* by the loaded cartridge acted upon by the magazine-spring, and that said cartridge-shell remains in the chamber *M*, to prevent the next loaded cartridge passing back into said chamber, and that when the wheel *I* is revolved the cartridge-shell is ejected from the chamber *M* while the carrier *G* is being revolved; hence said chamber is empty, ready for the reception of another shell, when the carrier has completed its half-revolution.

If, in consequence of any momentary excitement, the trigger *F* should be pulled too quickly, or if the spring-barrel *H* fails to completely rotate the shaft and tumbler *K*, it is important to prevent the trigger being pulled and the arm fired before the parts are in proper position for firing. To effect this object, I make use of a spring, *v*, at one side of the stationary lock-frame, and adjacent to the upper or moving end of the trigger-sear *s*, and upon this spring *v* there is a projecting-block, *v'*, which, coming in front of the trigger-sear *s*, effectually prevents the same being moved until the spring *v* and its block *v'* are pressed back. To effect this, I make an incline, *v²*, upon the upper end of the spring *v*, against which the side of the revolving tumbler *K* acts to press such spring back laterally, and the position of these parts is such that the incline *v²* is immediately behind the tumbler *K* when the end thereof is in contact with the sear *s*; hence the trigger-sear is unlocked only at the completion of the revolution of the tumbler *K*, and free to be moved forward when the parts are in proper position.

In some instances it is preferable to dispense with the shaft *p*, arm *p'*, and link *p²*, and to use the pin 12 as the pivot for both hinge-pieces of the door *m*, as seen in Fig. 27, and to extend upwardly the arm 14 upon the shaft *r'* as a curved arm sufficiently high to pass in behind the ejector *P*, as seen in Fig. 26, so that when the cam-disk *i*² revolves into contact with the arm *r*, and partially rotates the shaft *r'*, this arm 14 will swing the ejector *P* downward and forward and open the door *m*, and throw the cartridge out of the chamber *M*, thus simplifying the construction of the parts.

I claim as my invention—

1. The combination, with the magazine for cartridges and a carrier for conveying the cartridges from the magazine to the breech in

a fire-arm, of a spring-barrel capable of being wound up, and a chain from such barrel and gearing acted upon by the chain to revolve 70 the carrier progressively, substantially as set forth.

2. The combination, with the barrel and magazine in a fire-arm, of a carrier to convey the cartridges from the magazine to the breech, 75 a spring-barrel capable of being wound up, chain-wheels, and a chain from such barrel, and gearing for revolving the carrier, a reciprocating breech-bolt for conveying the cartridge from the carrier into the breech, a crank 80 and connecting-rod receiving motion from the spring-barrel chain, and wheels for giving a backward and forward motion to the reciprocating breech-bolt, substantially as specified.

3. The combination, with the barrel and reciprocating breech-bolt and its actuating mechanism, of a revolving carrier for bringing the cartridge up to the breech of the barrel, and having two openings for the cartridge, and longitudinal slots for the connection between 90 the reciprocating breech-bolt and its actuating mechanism, and a shaft and gearing for revolving the carrier, substantially as specified.

4. The combination, with the barrel and magazine, of a spring-barrel capable of being 95 wound up, chain-wheels, a chain, a revolving cartridge-carrier, a shaft for the same, a pinion upon the said shaft, sectional gearing acted upon by the chain for turning the pinion, and the stops for holding the pinion and carrier, substantially as set forth.

5. The combination, in a magazine fire-arm, of a revolving carrier at the rear of the breech for conveying the cartridges from the magazine to the breech, a reciprocating breech-bolt, a spring-barrel, chain, and chain-wheels, and sectional gearing for rotating the carrier and its shaft, and a tumbler, crank-pin, and connecting-rod for moving the reciprocating breech-bolt and forcing the cartridge from the 105 carrier into the barrel, substantially as set forth.

6. The combination, with the barrel and magazine, of a revolving carrier to convey the cartridges from the magazine to the breech, a reciprocating breech-bolt, toggle-links at the rear end of such breech-bolt, a spring capable of being wound up, a chain and chain-wheels, a shaft and gearing acted upon by such chain to rotate the carrier, a cam 115 revolved with the gearing to act upon the toggle-links and move them beyond the center, a spring to give the return-motion to the toggles, a crank-pin, and connecting-rod to reciprocate the breech-pin, substantially as set 120 forth.

7. The combination, with the magazine for the cartridges, the barrel, the carrier behind and upon an axis parallel with the barrel, and gearing for revolving the carrier, of a spring-barrel adapted to be wound up, a chain connecting the barrel and the carrier-operating mechanism, and chain-wheels, a hinged lever, and bearings for the shaft of the spring. 130

barrel, a pivot upon the frame of the butt, and a screw for tightening the chain, substantially as set forth.

8. The combination, with the magazine and barrel in a fire-arm, of a carrier for conveying the cartridges from the magazine to the breech, and gearing for revolving the same, of a spring-barrel in the stock of the gun, a chain, chain-wheels, and a guide-pulley for directing the chain in its passage through the stock of the gun, substantially as set forth.

9. The combination, in a fire-arm, with the magazine for cartridges, the barrel, and a revolving carrier to transfer the cartridges from the magazine to the breech, of a spring capable of being wound up, chain-wheels, and chain from the same, and sectional gearing for revolving the carrier, a tumbler revolved by the chain, a trigger, and sear for arresting the motion of the tumbler, a breech-bolt for moving the cartridge into the barrel, a firing-pin, a spring, and a sear for holding the firing-pin, substantially as specified, whereby the sear of the trigger discharges the firing-pin before allowing the tumbler to revolve, substantially as set forth.

10. The combination, in a fire-arm, with the revolving tumbler K, for operating the lock mechanism of the gun, of the trigger F', the trigger-sear s, latch s', hook f', the springs for the respective parts, and the spring-barrel capable of being wound up, and the chain and chain-wheels for giving motion to the tumbler, substantially as specified.

11. The combination, in a fire-arm, with the spring-barrel capable of being wound up and the chain and chain-wheels, of the tumbler K for operating the lock mechanism of the gun, having a notch, 26', the trigger F', and sear s, the firing-pin and its sear, and the arm n' upon the sear, and the hook f' upon the trigger, substantially as and for the purposes specified.

12. The combination, with the trigger F' and its sear s, of the firing-pin n, sear n' for the firing-pin, the arm n', connected with the sear n', joint 29, sear-spring and arm t', for holding the sear n', and the cartridge-carrier G, and its axle and sectional gearing for revolving the same, whereby the sear n' and firing-pin are locked and held while the trigger and sear are being moved for allowing the cartridge-carrier to be revolved, substantially as set forth.

13. The finger-piece t', vertical shaft t', supported in the housing, and safety-lock t upon the shaft t', to lock the parts, in combination with the revolving tumbler K, the trigger and trigger-sear between the tumbler and the safety-lock, the spring-barrel capable of being wound up, and the chain-wheels and chain for revolving the tumbler K, substantially as set forth.

14. The combination, with the fire-arm bar-

rel, the magazine for cartridges, and the revolving carrier behind the barrel, for conveying the cartridges successively from the magazine to the breech, of the stationary lock-frame I', for supporting the operating mechanism of the gun, having a filling and ejecting chamber, M, in line with the magazine, a swinging door to the same, an ejector within the chamber, and the crank-arm p' upon the axis of the swinging door, link r', cam-arm r, and revolving cam i', and operating mechanism for actuating the ejector, substantially as specified.

15. The combination, with the magazine, barrel, and revolving carrier upon an axis in line with the barrel, of the filling and ejecting chamber in the lock-frame and in line with the magazine, the gate q at the front end of the ejecting-chamber, the shaft q', and finger 15, the shaft r' in line with the shaft q', the finger 14, and cam-arm r upon the same, and the revolving cam i', for moving the arm r, chain and actuating spring for moving the parts, and swinging gate at the end of the filling and ejecting chamber, substantially as set forth.

16. The combination, with the barrel and magazine in a fire-arm, of a revolving carrier, an axis for the same parallel with the barrel, the stationary lock-frame having a filling and ejecting chamber in line with the magazine, a hinged door for said chamber, and a spring 95 for closing the same, a gate, q, at the front end of the ejecting-chamber, a thumb-piece, q', acted upon by the door of the ejecting-chamber and moving the gate, and an ejector within the chamber, and mechanism, substantially as specified, for giving motion to the respective parts, as set forth.

17. The combination, with the tumbler K and spring, capable of being wound up, of the chain and chain-wheels for revolving the tumbler, a trigger, F', and sear s beneath the revolving tumbler, a spring-lock, r, upon the stationary lock-frame for the trigger-sear, and an incline, v', upon said spring r, whereby the tumbler in its revolution unlocks the trigger-sear, substantially as set forth.

18. The combination, with the reciprocating breech-bolt and the firing-pin, of the sear n', to hold the firing-pin, the set-back o, pivoted within the breech-bolt and having a cam 115 end to act upon the firing-pin, the stationary projection o', with which an inclined face on the set-back comes into contact as the breech-bolt is drawn back, and the spring acting directly upon the set-back to return it to the normal position, substantially as set forth.

Signed by me this 8th day of April, A. D. 1885.

FRANK REES.
